(57) **CLAIM**

The ornamental design for a faucet as shown and described.

DESCRIPTION

Faucet

FIG. 1.1 is a perspective view of a faucet showing our new design;

FIG. 1.2 is a top view thereof;

FIG. 1.3 is a bottom view thereof;

FIG. 1.4 is a front view thereof;

FIG. 1.5 is a rear view thereof;

FIG. 1.6 is a right side view thereof; and

FIG. 1.7 is a left side view thereof.

The design is a faucet. The design is characterized by features represented in solid lines. Protection is not claimed for parts in broken or dotted lines.

1 Claim, 7 Drawing Sheets
